AUTOMATIC FLUID FLOW CONTROL UNIT

Walter C. Benzing, Saratoga, Calif., assignor to Applied Materials Technology, Inc., Santa Clara, Calif.

Filed Nov. 8, 1971, Ser. No. 196,875

Term of patent 14 years

Int. Cl. D24—01

U.S. Cl. D16—2 C

FIG. 1 is a perspective view of an automatic fluid flow control unit embodying my new design.

FIG. 2 is a top plan view thereof.

FIG. 3 is an elevational view taken from one side thereof.

FIG. 4 is a bottom plan view thereof.

FIG. 5 is an elevational view taken from the side opposite that shown in FIG. 3.

FIG. 6 is an end elevational view thereof.

I claim:

The ornamental design for an automatic fluid flow control unit, substantially as shown.
